UNITED STATES PATENT OFFICE.

JOACHIM E. BERLIEN, OF ALTONA, PRUSSIA, GERMANY.

MEANS FOR DRAWING CORKS FROM BOTTLES.

SPECIFICATION forming part of Letters Patent No. 278,388, dated May 29, 1883.

Application filed February 15, 1883. (No model.)

To all whom it may concern:

Be it known that I, JOACHIM EMIL BERLIEN, of Altona, in the Kingdom of Prussia, in the Empire of Germany, have invented a new and useful Improvement in Means for Drawing Corks from Bottles, of which the following is a specification, reference being had to the accompanying drawings.

This invention relates to the class of cork-drawing devices which consist of a strap, cord, or band driven into the mouth of a bottle or other vessel with the cork, and extending transversely across under or through the cork at or near its inner end, whereby provision is afforded for withdrawing the cork by pulling on the protruding ends of the strap, cord, or band. The object of my invention is to provide a convenient means for determining whether the bottle or vessel has been surreptitiously opened or uncorked.

The invention to this end consists in the combination, with a corked bottle or other vessel and a strap or band applied to the cork, as above described, of a label or seal applied to the exterior of the bottle or vessel and securing the end portions of the strap or band thereto. In order to bring the end portions of the strap or band upward into such a position that they can be pulled to draw the cork, they must be torn loose from the label or seal, and this cannot be done without its being readily detected. The band or strap should be prepared to resist the influence of the liquid contained in the vessel, and also for the purpose of preventing leakage, which would result from its capillarity in the unprepared state. In cases when bottles are corked by machinery or long corks are driven very tight or fast into the mouths of bottles, &c., the further preparation of the strap or band may be required to enable the corks to be drawn in the manner hereinafter described without tearing the strap or band. The friction between the strap and the bottle, &c., may be largely reduced by the preparation of the former. The substance by means of which the strap is prepared or treated is preferably wax, and that part of the strap which is to come in contact with the cork of the bottle is dipped into molten wax, and all superfluous portions of wax are afterward removed from the strap by scraping its surface with a knife or such like instrument. Other substances—as, for instance, paraffine—may be employed for preparing the strap; but wax is preferred, as it

exerts no influence upon the taste of the liquid inclosed in the bottle, jug, &c.

For drawing the cork of a bottle, jug, &c., closed in a manner as before described, the ends of the strap are torn from the outer surface of the bottle, and by pulling these both ends upward the cork is extracted by the strap.

Figure 1 of the annexed sheet of drawings represents in perspective the corked bottle with the ends of the strap secured by the label. Fig. 2 is a perspective view of the corked bottle with the strap unfastened and in position for drawing the cork. Fig. 3 is a cross-section of the neck of the bottle, the cork, and the strap.

B is the strap, partly prepared in the manner described, and which is, together with the cork, driven into the neck of the bottle.

D represents a label or seal employed to attach the ends of the strap to the outer side of the bottle, as shown in Fig. 1.

To draw the cork from the bottle, the ends of the strap or band B are torn away from the label or seal D, and are wound round a finger or round the hand, and are pulled upward, as shown in Fig. 2. As the friction between the cork and the bottle is partly reduced by the smooth prepared strap B, there is no difficulty in extracting corks of wine-bottles or other large bottles corked by machinery or otherwise.

When the end portions of the strap or band are secured as above described they cannot be detached and brought upward into a position for drawing the cork without tearing or defacing the label or seal, and hence a ready means is afforded for determining whether the cork has been surreptitiously withdrawn.

What I claim as my invention, and desire to secure by Letters Patent, is—

The combination, with a corked bottle or other corked vessel, of the strap or band B, passing across the cork and between it and the mouth of the bottle, and having its end portions projecting beyond the mouth, and a label or seal, D, applied to the exterior of the bottle or vessel, and securing the end portions of the strap or band thereto, substantially as and for the purpose herein described.

JOACHIM EMIL BERLIEN.
